HOSIERY INSPECTION AND REPAIR FORM

Douglas P. Dameron and Floyd R. Shoaf, Concord, N. C., assignors of one-half to said Shoaf and one-half to Jacob R. Livengood, Jr., of Concord, N. C.

Application November 17, 1947, Serial No. 786,520

8 Claims. (Cl. 223—75)

1

This invention relates to a hosiery inspection and repair form and more especially to a form onto which a stocking can be placed for inspecting the same and which at the same time can be used for repairing runs, pull threads and the like while the stocking is on the form.

It is an object of this invention to provide a hosiery inspection and repair form having a frame comprising an inverted U-shaped member and said inverted U-shaped member having extending from opposed sides thereof bowed members for stretching the stocking at the proper points, some of the bowed members extending out further at some points along the form than at others so as to stretch the stocking in conformity to its width at various points, and which form is preferably composed of transparent plastic material. Also, if desired, a suitable plastic or other board, which is preferably black, but at least of opaque material, can be disposed between and held in place by the U-shaped form and whereby a background will be provided making visible only one half of the stocking at a time and the imperfections on the far side of the form from the operator not being visible and thus preventing confusion as to on which side of the stocking the imperfections are located.

Some of the objects of the invention having been stated, other objects will appear as the description proceeds when taken in connection with the accompanying drawings, in which

Figure 1 is a side elevation of the form;

Figure 2 is an edge view of Figure 1 looking from the right-hand side of Figure 1;

Figure 3 is a vertical sectional view taken along the line 3—3 in Figure 1 and showing a portion of a stocking thereon;

Figure 4 is a transverse sectional view taken along the line 4—4 in Figure 1.

Referring more specifically to the drawings, the numerals 10 and 11 indicate the substantially vertically disposed legs of a U-shaped frame member indicated broadly at 12. The lower ends of the legs 10 and 11 have secured thereto a suitable base member 14 by any suitable means such as screws 15 and this base member may be secured to a suitable table top or a stand 16 by any suitable means such as a screw 17. The proximate surfaces of the legs 10 and 11 as well as the top-most portion 20 of the form, have a continuous groove 21 therein in which may be disposed, if desired, an opaque board 22 which will permit inspection of one side of the stocking only at a time, and since the base 14 is mounted with a centrally disposed screw 17, the form can then be

2

rotated, if desired, to present the other side to the operator without the operator's having to walk around to the other side of the form.

The legs 10 and 11 have suitable cavities in each side thereof in which are glued or otherwise secured the ends of suitable bowed or curved bridging members for stretching or extending the stocking to the proper size for inspection and repair work. These bowed members are divided into groups and near the top of the legs 10 and 11 is a first group including three outwardly bowed members 24 which are of approximately the same size. The bowed members 24 which have their ends glued into suitable cavities in the leg members 10 and 11, all project outwardly about the same amount from the front side of the legs 10 and 11 and are adapted to fit into and to distend the top portion of the foot of the stocking. The bowed member 25 occurring on the other or rear side of the legs 10 and 11 projects into the beginning of the heel portion and the bowed member 26 projects into the main heel portion of the stocking. The bowed member 27 on the front side of the form projects into the instep portion while the members 28 and 29 on opposite sides of the legs 10 and 11 properly distend the ankle portion of the stocking. The bowed members 25, 26 and 27 comprise a second group and the members 28 and 29 may comprise a third group.

The bowed members 30 and 31 are substantially larger than the bowed members 26 and 27, for example, and fit into the lower leg portion. The bowed members 32 and 33 project outwardly slightly further than the members 30 and 31 and fit into the enlarging leg portion while the bowed members 34 and 35 are substantially larger than the bowed members preceding them. The next set of bowed members 36 and 37 are slightly larger than the preceding bowed members 34 and 35, while the bowed members 38 and 39 are substantially larger than the bowed members 36 and 37.

The bowed members 40 and 41 are substantially the same size as bowed members 38 and 39. The bowed members 42, 43, 44, 45, 46 and 47 are of gradually diminishing size with respect to outward bulge so as to begin to relieve the strain on the welt or shadow welt of the stocking. The bowed members 48 and 49 are slightly larger than the bowed members 46 and 47 while the bowed members 50 and 51 are of slightly lesser outward bulge than the preceding bowed members 48 and 49. The purpose of this diminishing from 55 42 and 43 down to the bottom bowed members 50

and 51 is to relieve the tension on the welt portion of the stocking which is adapted to be placed over these bowed members and in case of a longer stocking, the welt would sometimes be disposed down below the lower bowed members 50 and 51, as it is not good practice to impart very much strain or stretch to the welt portion of the stocking. The stocking is indicated by reference character S in Figure 3 and is omitted in the other views for sake of clearness. The bowed members 30 to 51 constitute a fourth group of outwardly bowed or curved bridging members.

It is apparent that if a stocking, which is usually in the greige, that is before coloring and finishing, is placed on this form and the parts of the form being transparent, that in looking at one side of the stocking, the other side would also be visible. It is preferable then to place an opaque board 22, preferably black and made of suitable plastic, within the groove 21, this board being cut to fit the inside surfaces of the groove 21 on the proximate sides of the legs 10 and 11 and thus only one half of the stocking can be seen at a time and since the bowed members hold the stocking substantially outward from this plastic member, there is still sufficient room for a repair needle to be reciprocated back and forth relative to the fabric for repairing runs and the like without striking the plastic board 22.

It is thus seen that there has been provided an inspection and repair form for stockings which has many advantages over other forms heretofore used.

In the drawings and specification there has been set forth a preferred embodiment of the invention, and although specific terms are employed, they are used in a generic and descriptive sense only and not for purposes of limitation, the scope of the invention being stated in the claims.

We claim:

1. A hosiery inspection and repair form comprising a substantially inverted U-shaped member formed from a single piece of transparent plastic material and having ribs extending transversely thereof and bowed outwardly with respect to the inverted U-shaped member to stretch a stocking which has been placed over the same and whereby the stocking when inspected can be repaired while on the form, and an opaque board-like member disposed between and secured to the proximate surfaces of the legs of the U-shaped member to cause only one-half of the stocking to be visible at a time to an inspector.

2. A hosiery inspection form comprising an inverted U-shaped member and a suitable base to which the lower ends of the U-shaped member are secured, said U-shaped member having a plurality of horizontally disposed outwardly bowed members extending from opposed sides thereof so that when a stocking is inserted over the form it will distend the same and enable an operator to not only detect imperfections in the stocking while on the form, but also permitting manipulation of a run repair needle and the like through the stocking for repair purposes, and an opaque board secured within the U-shaped member and serving as a background for one-half of the stocking at the time so as to enable runs and other imperfections to be more discernible and the bowed members holding the stocking far enough away from the board to permit a run repair needle and the like to be manipulated through the fabric for repairing of the stocking while on the form.

3. A hosiery inspection and repair form com-

prising a substantially inverted U-shaped member formed from a single piece of transparent plastic material and having ribs extending transversely thereof and bowed outwardly with respect to the inverted U-shaped member to stretch a stocking which has been placed over the same and whereby the stocking when inspected can be repaired while on the form, and an opaque board-like member disposed between and secured to the proximate surfaces of the legs of the inverted U-shaped member to cause only one-half of the stocking to be visible at a time to an inspector, a base secured to the lower end of the form and means for rotatably mounting the base on an axis parallel to the longitudinal axis of the form.

4. A hosiery inspection form comprising an inverted U-shaped member and a suitable base to which the lower ends of the U-shaped member are secured, said U-shaped member having a plurality of horizontally disposed outwardly bowed members extending from opposed sides thereof so that when a stocking is inserted over the form it will distend the same and enable an operator to not only detect imperfections in the stocking while on the form, but also permitting manipulation of a run repair needle and the like through the stocking for repair purposes, and an opaque board secured within the U-shaped member and serving as a background for one-half of the stocking at the time so as to enable runs and other imperfections to be more discernible and the bowed members holding the stocking far enough away from the board to permit a run repair needle and the like to be manipulated through the fabric for repairing of the stocking while on the form, the base having means for rotatably mounting the same on an axis parallel to the longitudinal axis of the form.

5. A hosiery inspection form comprising an inverted substantially U-shaped frame member provided with spaced vertically disposed legs, said legs being bowed outwardly intermediate their ends with respect to each other, a plurality of first vertically spaced horizontally disposed outwardly bowed members each having in-turned end portions secured to the front surfaces of the legs of the U-shaped member adjacent the upper end thereof for supporting the foot portion of a stocking, a plurality of second outwardly bowed members having in-turned end portions secured to the rear surfaces of said legs and spaced immediately below the horizontal plane of the first outwardly bowed members for supporting a heel portion of a stocking, third outwardly bowed members spaced immediately below the second outwardly bowed members and having in-turned end portions of less length than the first outwardly bowed members and being secured to the front and rear surfaces, respectively, of said legs, a plurality of fourth vertically spaced outwardly bowed members on the front and rear sides of said legs and spaced below the third bowed members and having in-turned end portions secured to the front and rear surfaces of said legs and the in-turned portions thereof gradually increasing in length from adjacent the third outwardly bowed members to a point substantially midway of the legs and the in-turned end portions then gradually decreasing in length from said point to a point adjacent the lower ends of the legs.

6. A hosiery inspection and repair form comprising an inverted U-shaped frame provided with a pair of spaced vertically disposed legs having front and rear surfaces, a plurality of horizontally disposed vertically spaced outwardly

curved bridging members projecting forwardly and rearwardly from the respective front and rear surfaces of said legs, said bridging members being divided into first, second, third and fourth groups, said first group being disposed adjacent the upper end of the frame and projecting from the front surface only for supporting the foot of a stocking, said second group being spaced immediately below the first group and projecting outwardly a greater distance from said legs than the first group and being on both the front and rear sides of said legs for supporting the heel and instep portions of a stocking, said third group being spaced below the second group and projecting from the front and rear sides of said legs a lesser amount than the second group for supporting the ankle of a stocking, said fourth group being spaced below the third group and also being on both the front and rear sides of said legs, the distance the bridging members of said fourth group project from the front and rear surfaces of the legs gradually increasing from adjacent the third group to a point substantially midway of the legs and the distance that the bridging members in the fourth group project then gradually decreasing from midway of the legs to a point adjacent the lower ends of the legs for supporting the leg and welt of a stocking.

7. A hosiery inspection form comprising an inverted substantially U-shaped frame member provided with spaced vertically disposed legs, said legs being bowed outwardly intermediate their ends with respect to each other, a plurality of first vertically spaced horizontally disposed outwardly bowed members each having in-turned end portions secured to the front surfaces of the legs of the U-shaped member adjacent the upper end thereof for supporting the foot portion of a stocking, a plurality of second outwardly bowed members having in-turned end portions secured to the rear surfaces of said legs and spaced immediately below the horizontal plane of the first outwardly bowed members for supporting a heel portion of a stocking, third outwardly bowed members spaced immediately below the second outwardly bowed members and having in-turned end portions of less length than the first outwardly bowed members and being secured to the front and rear surfaces, respectively, of said legs, a plurality of fourth vertically spaced outwardly bowed members on the front and rear sides of said legs and spaced below the third bowed members and having in-turned end portions secured to the front and rear surfaces of said legs and the in-turned portions thereof gradually increasing in length from adjacent the third outwardly bowed members to a point substantially midway of the legs and the in-turned end portions then gradually decreasing in length from said point to a point adjacent the lower

ends of the legs, the lowermost of said fourth outwardly bowed members being disposed a substantial distance from the lower ends of the legs to accommodate the welt of a stocking and to relieve strain thereon during inspection of the stocking.

8. A hosiery inspection and repair form comprising an inverted U-shaped frame provided with a pair of spaced vertically disposed legs having front and rear surfaces, a plurality of horizontally disposed vertically spaced outwardly curved bridging members projecting forwardly and rearwardly from the respective front and rear surfaces of said legs, said bridging members being divided into first, second, third and fourth groups, said first group being disposed adjacent the upper end of the frame and projecting from the front surface only for supporting the foot of a stocking, said second group being spaced immediately below the first group and projecting outwardly a greater distance from said legs than the first group and being on both the front and rear sides of said legs for supporting the heel and instep portions of a stocking, said third group being spaced below the second group and projecting from the front and rear sides of said legs a lesser amount than the second group for supporting the ankle of a stocking, said fourth group being spaced below the third group and also being on both the front and rear sides of said legs, the distance the bridging members of said fourth group project from the front and rear surfaces of the legs gradually increasing from adjacent the third group to a point substantially midway of the legs and the distance that the bridging members in the fourth group project then gradually decreasing from midway of the legs to a point adjacent the lower ends of the legs for supporting the leg and welt of a stocking, the lowermost of the bridging members in said fourth group being spaced substantially from the lower ends of the legs so the welt of a stocking may be disposed below the lowermost of the bridging members in the fourth group to relieve strain on the welt during inspection and repairing of the stocking.
